UNITED STATES PATENT OFFICE.

CARL HOCHSTADT, OF CHICAGO, ILLINOIS, ASSIGNOR TO MARDER, LUSE & CO., OF SAME PLACE.

TYPE-CASTING MOLD.

SPECIFICATION forming part of Letters Patent No. 336,483, dated February 16, 1886.

Application filed July 13, 1885. Serial No. 171,411. (No model.)

To all whom it may concern:

Be it known that I, CARL HOCHSTADT, a citizen of the United States of America, residing at Chicago, in the county of Cook and State of Illinois, have invented certain new and useful Improvements in Type-Casting Molds, of which the following is a specification, reference being had therein to the accompanying drawings.

10 The object of my invention is to facilitate the casting of types with a groove or recess, in which smaller type may be placed, by firmly securing a core within a type-casting mold and furnishing said core with a movable rod 15 passing through its center, for the purpose of quickly separating the grooved type from the core and mold.

In the accompanying drawings, Figure 1 is a front view of a type-casting mold embodying my invention. Fig. 2 is a horizontal section on line *x* *x* of Fig. 1. Fig. 3 is a perspective view of one of the types produced. Fig. 4 is a vertical section through the core and type, showing the discharge of type from the mold. Fig. 5 is a view of a portion of the lower half of a type-casting mold. Fig. 6 25 illustrates the use of said type.

The parts A A' A'', and other parts not herein specifically described, of my type-casting mold are of the usual construction.

B designates a core firmly held in the mold by screws, as shown in Figs. 4 and 5.

C designates a cylindrical opening through the longitudinal center of the core, to receive the movable rod D, extending entirely through the core. The outer end, *b*, of the movable rod is pivoted to a lever, E, the end *c* of which is pivoted to an arm, *d*, which is pivoted to the

part A² of the mold. The removable rod is provided with a collar, *f*, having a threaded hole to receive the set-screw F, to secure the rod in place, so that it may not be withdrawn entirely from the matrix-space, to prevent the formation of a projection on the side of the type G in casting it.

In the operation of molding the type, the metal being run into the matrix-space and allowed to cool, the mold is opened, and by means of the lever the rod is projected beyond the face of the core against the type, 50 separating it from the mold, as shown in Fig. 4. The rod is then withdrawn and secured in place by the set-screw with the inner end flush with the face of the core, the mold is closed, and the operation of molding and removing the type continued, as above described.

What I claim as new, and desire to secure by Letters Patent, is—

1. In a mold for casting grooved type, a perforated core firmly fixed in the mold, in combination with a movable rod attached to the mold and adapted to separate the type from the core, substantially as and for the purpose described.

2. In a type-casting mold, the core B, having a longitudinal opening, C, in combination with the movable rod D, extended through the core, and the lever E, pivoted to the mold and the rod, substantially as and for the purposes described.

In testimony whereof I have affixed my signature in presence of two witnesses.

CARL HOCHSTADT.
